James M. Eiffe INVENTOR.

BY
S. E. Thomas

ATTORNEY.

UNITED STATES PATENT OFFICE.

JAMES M. EIFFE, OF FULTONVILLE, NEW YORK, ASSIGNEE TO WHITE MOP WRINGER COMPANY, OF FULTONVILLE, NEW YORK, A CORPORATION OF NEW YORK.

MOP WRINGER.

Application filed December 15, 1926. Serial No. 154,892.

My invention relates to an improvement in mop wringers shown in the accompanying drawings and more particularly described in the following specification and claims.

- 5 This invention relates to the type of mop wringer in which the wringing mechanism includes a jointed frame with one portion adapted for attachment to a pail,—the other portion being pivoted to the first named 60 portion with a pair of rollers respectively journaled in said fixed and stationary portions of the frame so that upon rocking the swinging portion of the frame the rollers may be separated to admit a mop between 65 the rollers which when closed upon the mop and manually rotated will operate to express water from the latter.

One of the objects of the present invention is to so construct the swinging frame 20 that the operator may bear upon the latter with his knee, thereby exerting pressure through the rollers upon the mop while manually rotating one of the rollers to express water therefrom,—a concave depression 25 being provided in the frame that the knee of the operator may not slip off the frame when pressure is applied.

A further object of the invention is to construct the swinging portion of the frame 30 with one or more arms of relatively different length to provide for gradational leverage,—both arms having a concave formation to receive the operator's knee that the latter may not slip from the frame when exerting 35 pressure upon the mop through the rollers while manually turning the latter to express water therefrom.

A further object of this invention is to provide means for guiding the mop so that 40 the threads of the mop may not become entangled with the shaft of the roller and the supporting frame, the purpose of the guides being to protect the mop from becoming entangled with the shaft while turning the 45 roller.

A further object of the invention is to provide means whereby the pressure of the knee of the operator upon the swinging frame may be exerted without danger of tipping the pail and spilling its contents.

A further object of the invention is to provide means whereby the wringer may be secured to the wall of a pail without danger of the wringer becoming loosened in use.

55 With the foregoing and other objects in

view which will appear as the description proceeds, the invention further resides in the combination and arrangement of parts and in the details of construction hereinafter described and claimed, it being understood that changes may be made in the precise embodiment of the invention herein disclosed without departing from the spirit of the same.

In the drawings accompanying this specification and forming a part thereof:

Figure 1 is a plan view of a mop wringer secured to the wall of a pail and showing the swinging frame "open" to receive a mop between its rollers.

Figure 2 is a side elevation of the device shown in Figure 1 with parts broken away and in section.

Figure 3 is a fragmentary view with parts broken away and in section, showing the 75 swinging frame with the rollers journaled therein closed upon a mop as when expressing water therefrom.

Figure 4 is a plan view of a modification comprising a detachable frame secured to a 80 pail—indicated in dotted lines—with the wringing rollers in "open" position to receive a mop.

Figure 5 is a cross-sectional elevation taken on or about line 5—5 of Figure 4.

Figure 6 is a sectional elevation of the device mounted upon a pail—indicated in dotted lines—showing the wringing rollers in "closed" relation as when expressing water from the mop.

Figure 7 is a fragmentary plan and sectional view taken on or about line 7—7 of Figure 5, showing a fragment of the pail between the depending lugs of the frame and secured thereto through the adjustment of a 95 thumb-screw.

Figure 8 is a fragmentary sectional view taken on or about line 8—8 of Figure 4.

Referring now to the letters of reference placed upon the drawings:

A denotes a pail upon which is mounted a wringer B including a frame consisting of two hinged members C and D. The member C is fixedly secured to the pail while the member D is pivoted at F to the fixed frame. 105 Journaled in the fixed frame C is a corrugated roller E, and journaled in the swinging frame D is a corrugated roller G, the shaft G¹ of which projects beyond the wall of the pail and is fitted with a crank arm G². 110

for manually operating the roller. Projecting rearwardly from the arc-shaped portion D^1 of the swinging frame is an arm D^2 having a concave depression D^3 on its upper face to accommodate the knee of the operator.

Adjacent to the arm D^2 and integral with the arc-shaped portion of the swinging frame is a relatively shorter arm D^4 which 10 is also formed with a cup-shaped depression D^5 on its upper face to receive the knee of the operator. $H-H$ are guide members to direct the mop away from the ends of the corrugated rollers that the threads of the 15 mop may not become entangled between the ends of the roller and the bearings supporting its shaft.

In the modification shown in Figures 4 and 5 these guides consist of an extension 20 C^a of the stationary frame projecting below the corrugated roller;—the stationary frame also overlaps the front of the roller to direct the threads of the mop away from the ends of the roller when expressing water from 25 the mop.

In the modification shown in Figures 4 and 5 the "fixed" frame is provided with staggered lugs C^b C^b one of which is provided with a thumb or set screw C^d which 30 when adjusted will engage the wall of the pail bending the same slightly that it may impinge against the lugs as shown in Figure 7, thereby insuring a rigid mounting of the frame upon the pail. I is a lug projecting from the wall at the bottom of the pail 35 to prevent the pail tipping under the pressure of the operator's knee when in the position shown in Figure 3.

Having indicated the several parts by reference letters, the construction and operation 40 of the device will be readily understood.

When it is desired to express water from the mop, the swinging frame is tilted to the 45 position indicated in Figures 1, 2, 4 and 5 that the mop may be inserted between the corrugated rollers. The swinging frame is then shifted to the position indicated in Figures 3 and 6; the operator resting his knee upon either of the extensions of the swinging frame dependent upon the pressure he 50 desires to exert. The crank arm G^e is then manually rotated, forcing the water from

the mop through the action of the corrugated rollers.

It will be seen that the concave formation 55 of the arms D^2 D^4 on which the operator rests his knee will insure against slippage of the knee of the operator when applying pressure to the swinging frame. This feature of the invention has through use been 60 found of great advantage, as without the depression it is difficult to maintain the knee upon the projections while applying pressure simultaneously with the rotation of the wringing rollers.

By providing extensions of relatively different lengths, the pressure applied may be graduated to meet the requirements of the mop.

Having thus described my invention what 70 I claim is:

1. In combination with a pail, a mop wringer comprising a fixed and a swinging frame, the swinging frame being hinged to the fixed frame, the fixed frame being adapted to be secured to the pail; a roller journaled in the fixed frame; a roller journaled in the swinging frame; a crank arm secured to the shaft of one of said rollers, whereby it may be manually rotated, said swinging frame having a concave depression adapted 80 to receive the knee of the operator, whereby pressure may be applied to the swinging frame when expressing water from the mop upon manual rotation of the rollers.

2. In combination with a pail, a mop wringer comprising a fixed and swinging frame, the swinging frame being hinged to the fixed frame, said fixed frame being adapted to be secured to the pail; a roller journaled in the fixed frame; a roller journaled in the swinging frame provided with a crank arm secured to the shaft of the roller, whereby it may be manually rotated; a plurality of arms of relatively different 95 lengths projecting from the swinging frame having concave depressions to receive the knee of the operator, whereby pressure may be applied to the mop when expressing water therefrom through the rotation of the 100 rollers.

In testimony whereof, I sign this specification:

JAMES M. EIFFE.
